CLAIM

I claim the ornamental design for a tube securing device, as shown and described.

DESCRIPTION

FIG. 1 is a front, top, and right side perspective view of a tube securing device showing our new design;

FIG. 2 is a front elevation view thereof;

FIG. 3 a rear elevation view thereof;

FIG. 4 is a right side view thereof;

FIG. 5 is a left side view thereof;

FIG. 6 is a top plan view thereof; and,

FIG. 7 is a bottom plan view thereof.

The strap of the tube securing device is shown with symbolic break lines in its length. The appearance of any portion of the article between the break lines forms no part of the claimed design.
